(57) **CLAIM**

The ornamental design for a bed, as shown and described.

DESCRIPTION

FIG. 1 is a left front perspective view of a headboard and footboard showing my new design;

FIG. 2 is a side elevational view of the headboard and footboard;

FIG. 3 is a front elevational view of the headboard;
FIG. 4 is a front elevational view of the footboard; and,
FIG. 5 is a perspective view of the footboard from the inside.
The broken lines showing the bed rails is for illustrative purposes only and forms no part of the claimed invention.
